UNITED STATES PATENT OFFICE.

GEORGE H. BARRUS, OF BOSTON, MASSACHUSETTS.

DRAINAGE SYSTEM.

Application filed July 28, 1922. Serial No. 578,034.

To all whom it may concern:

Be it known that I, GEORGE H. BARRUS, a citizen of the United States, residing at Boston, in the county of Suffolk, State of Massachusetts, have invented certain new and useful Improvements in Drainage Systems; and I do hereby declare the following to be a full, clear, and exact description of the invention, such as will enable others skilled in the art to which it appertains to make and use the same.

This invention relates to steam heating systems comprising a multiplicity of units, and has to do particularly with a system in which the individual heating units are revolving drying cylinders of the type commonly employed in paper making machines, and the like. More specifically, the invention contemplates certain improvements and modifications in the structure disclosed in my United States Patent No. 1,192,369.

In machines of this character each of the revolving drying cylinders is commonly provided with a hollow bearing or trunnion through which the steam for heating the drying surface of the cylinder is passed and also through which the condensate is withdrawn from the unit. Two types of drainage systems for removing the accumulated condensate from the interior of the drying cylinders are in common use at present. In one of these systems, known as the "bucket type", a plurality of scoops or buckets are secured to the inner wall of the drying cylinder so that at every revolution of the cylinder each bucket, during the lower portion of its travel, takes up a quantity of the condensed water and then empties it into a suitable trough or discharge passage during the subsequent portion of its rotation. In the type of drainage system known as the "siphon system" the discharge passage for conveying the condensate out of the drying cylinder assumes the form of a pipe entering the cylinder through the hollow trunnion and thence extending downwardly within the cylinder so that its open end is positioned a short distance from the cylindrical wall of the cylinder at its lowest point. This siphon pipe is stationary and water may accumulate within the cylinder until the open end of the pipe is submerged. With this condition discharge of the con-

densate will occur provided that sufficient pressure difference exists between the interior of the cylinder and the discharge main to produce a flow through the siphon pipe.

The bucket system of drainage has the advantage that the discharge flow is not dependent at low speeds on the presence of a certain pressure difference between the interior of the cylinder and the discharge main. However, the effectiveness of the bucket system decreases as the speed of the drying rollers is increased due to the fact that the water condensate tends to accumulate at the outer walls of the cylinders under the action of the centrifugal force of rotation. As a result, even with moderate cylinder speeds, the water is held by the action of centrifugal force in the buckets until the buckets are elevated considerably above the axis of the cylinder. The time allowed for the condensate to run out is thus materially diminished and, in fact, this system of drainage may become entirely inoperative for high speed machines such as are commonly employed in the manufacture of paper.

On the other hand, with the siphon system the pressure required within the drying cylinder to lift the water from the end of the siphon to the center of the hollow trunnion and establish a flow is often unavailable at the proper time and, as a result, water accumulates within the cylinder to a considerable depth before a discharge flow is established. When the flow once starts it continues in considerable volume until the cylinder is emptied, whereupon the pressure within the cylinder is relieved due to the fact that the water falls below the opening in the siphon pipe and thus connects the interior of the cylinder directly with the discharge main. It is readily seen that the drainage with the siphon system is likely to occur in gulps, and that moreover during that portion of the operation in which large quantities of water have accumulated within the cylinder the power required to turn the cylinders is greatly increased and the drying capacity of the cylinders is correspondingly reduced.

In neither of the above types of drainage is there any provision for the discharge of

air which may accumulate in the drying cylinders and decrease the heat transferring efficiency of the drying surfaces.

One object of the invention is to prevent 5 the accumulation of condensation water in the drying cylinder, and at the same time to effect a continuous discharge of the condensate together with accumulated air from the drying cylinders. It is applicable to 10 either system of drainage, but since the bucket system is subject to unavoidable limitations due to its inability to function properly at high or even moderate speeds, I preferably employ the siphon system of drainage, but provide means for continuously maintaining an adequate pressure difference 15 between the interior of the cylinders and the drainage main so that a continuous outflow of the condensate will occur at all times. 20 In this manner I reduce the amount of condensate present within the cylinders at any time to a minimum, which quantity is determined by the distance of the opening at the inlet end of the siphon pipe from the adjacent 25 portion of the cylinder wall. Due to the continuous character of the discharge the level of the condensate is maintained at all times substantially flush with the opening in the siphon pipe and for this reason 30 there is afforded ample opportunity for the accumulated air within the cylinder, together with a portion of the uncondensed steam, to enter the siphon pipe and be conducted out of the cylinder. I also provide means 35 for maintaining within each cylinder a pressure sufficient to maintain a substantially continuous flow along the siphon pipe and into the discharge main.

It is also an object of the invention to provide 40 a heating system of this type in which the uncondensed steam issuing from the drying cylinders may be efficiently and conveniently separated from the condensate in order that its available heat may be utilized 45 in certain of the heating elements of the system, or in any other manner as desired.

It is a further object to provide a system 50 of the above type in which the apparatus provided for separating out uncondensed steam from the liquid condensate and permitting only condensed liquid to be discharged from the system is inexpensive and of relatively small dimensions, so that the provision of a special pit or compartment 55 for housing this portion of the system is not required.

It is a still further object to provide in 60 connection with the heating system a single indicating element capable of registering the pressure existing in the various parts of the system so that proper operating conditions may be maintained, and to provide means by which the level of the condensate in the drainage system may be determined 65 in order that sufficient space may be allowed

for the uncondensed vapor to flow and to separate out.

It is a still further object to provide in a system of this type an improved element of simple, inexpensive and durable construction for continuously maintaining a sufficient pressure difference between the interior of each drying cylinder and the drainage main to insure a continuous discharge 75 from the cylinder.

In the accompanying drawings I have illustrated a drying apparatus of the revolving cylinder type embodying my invention. The apparatus shown is of the type commonly employed in paper mills. In the 80 said drawings Figure 1 is a side elevational view showing the essential parts of the system; Fig. 2 is a partial vertical transverse view; Fig. 3 is a detail view of a modified portion of the system; Fig. 4 is a partial 85 side elevation, similar to Fig. 1, showing a somewhat modified system; and, Fig. 5 is a detail view of a portion of the apparatus.

Referring to the drawings, 1 indicates a drying cylinder positioned at one end of an apparatus comprising a plurality of cylinders, the remaining drying cylinders being indicated by the reference numeral 2. The cylinder 1 is preferably located at the "wet" 90 or initial end of the apparatus, although this arrangement is not essential to my invention. Each of the drying cylinders is rotatably mounted upon the frame of the apparatus and is provided with a hollow bearing or trunnion, as indicated at 3, and through which extends the inlet and discharge passages for the heating medium supplied to the cylinders. Steam from any suitable source is furnished to the supply 95 main 4 and individual branch lines 5 communicating with the main 4 serve to supply the respective drying cylinders with heating steam. The siphon system of drainage is employed, each cylinder being equipped with a siphon pipe 6, as shown in Fig. 2.

The pipe 6 enters the cylinder through the hollow trunnion 3 and has its portion within the cylinder bent downwardly so that the opening at the inner end of the pipe rests a short distance above the lowermost point of the cylindrical wall of the drying element. The condensate entering the siphon pipe 6 is conveyed out of the cylinder through the hollow trunnion 3 and into the main return header 7 by means of the individual discharge lines 8 extending from each cylinder into the header 7.

In each of the individual drainage lines 8 there is provided at 9 a constricted portion or passage which serves to limit the outflow from the cylinder. By properly adjusting the cross section of this restricted portion of the passage a back pressure may be established within the cylinder, which back pressure will be sufficiently great to 100 105 110 115 120 125 130

establish and maintain a continuous flow through the siphon pipe 6 and discharge line 8 into the main return header 7. The constricted portion 9 of the passage may 5 simply be a valve which is maintained partly closed or may be a gate valve in which a notch is cut for the purpose of affording a passage of restricted cross section, as illustrated in my above-mentioned patent. I 10 preferably, however, form the restricted passage 9 by means of a metallic disc having a centrally located orifice, as shown in detail in Fig. 9. This disc may be conveniently incorporated into the pipe line by inserting 15 it at the junction between two lengths of pipe, as shown, the cross section of the fluid passage at that point being reduced in dimension to the size of the orifice provided in the metal disc. A copper disc provided 20 with such orifice gives excellent service under the conditions met in systems of this type. It is readily seen that inasmuch as the flow through the orifice can occur only at a given rate by properly adjusting the 25 dimensions of the orifice the pressure within each drying cylinder may be raised sufficiently above that of the return header to insure a continuous discharge flow. Under such conditions the liquid level within the 30 cylinder will be maintained at substantially the level of the open end of the siphon pipe 6, and not only will the condensate be continuously withdrawn from the cylinder but also a certain amount of the uncon- 35 densated steam together with the air accumu- lating within the cylinder will be dis- charged. For the purpose of protecting the 40 constricted portion 9 of the discharge passage from becoming clogged by the gradual accumulation of dirt, the orifice disc is pre- 45 ferably inserted in the line 8 at a point just below a bend in the line, as shown at 10. The line 8 is extended somewhat past the elbow 10, as indicated at 11, so that what- 50 ever impurities issue from the cylinder will tend to continue on and accumulate in the blind branch 11 of the pipe. A chamber 11^a 55 may be provided at the lower end of the branch 11 for collecting the accumulated 60 sediment and affording a means for its ready removal.

It is seen that a certain amount of uncon- 65 densed steam will be discharged from the various cylinders 2 into the main return header 7, along with the condensed liquid. This steam will naturally tend to separate 70 out from the body of condensate and ac- cumulate in the upper portion of the header 7, at the same time moving along the length 75 of the header in a direction the same as that in which the liquid is flowing. At the outlet end of the header 7 there is provided 80 a loop containing two adjacent lengths of vertical piping 12 and 13. The liquid con- densate in the return header flows down into 85 the vertical pipe 12 while the vapor, due to its lesser specific gravity, tends to continue on beyond the junction of the pipe 12 with the header 7. Thus an effective separation 90 of the vapor from the liquid is accomplished by the influence of gravity alone and the vapor passes up through the line 14 and serves as a heating medium for the drying cylinder 1, after which it is discharged in 95 the manner above described through the line 8^a into the pipe 15 leading to the hot well or other place of disposal for the liquid con- densate.

The vertical loop consisting primarily of 100 the lengths of piping 12 and 13 is provided for the purpose of permitting only liquid condensate to pass into the line 15 leading to the hot well, and to cause all the uncondensed vapor to pass up through the supply line 14 into the drying cylinder 1. In appa- 105 ratus of this type as sometimes constructed the vertical arm 13 of the loop is made ap- preciably longer than the arm 12 so that the additional height of the water column in the arm 13 will be sufficient to compensate 110 for the excess of pressure existing in the return header 7 over that which exists in line 15 leading to the hot well. This type of construction is, however, objectionable in 115 that it is not uncommon for the pipe 13 con- stituting one side of the loop to reach a length as great as 60 feet, or where both are of the same length, to extend into the ground that extreme distance. It is obvious 120 that the provision of a pit or other place of disposal for such a great length of vertical pipe results in a great deal of additional expense in the installation of the apparatus. To overcome this difficulty I have con- 125 stricted a portion of the passage in the pipe 13 in such manner that by means of a constriction a back pressure may be estab- lished upon the liquid endeavoring to flow up through the pipe 13 which pressure is the equivalent of that ordinarily supplied by the additional weight of the water col- 130 umn provided in an elongated arm 13. This constricted passage may consist merely of a valve provided in the pipe 13, but for the purpose of adjustment I preferably provide an open pipe 16 of cross section smaller than that of the pipe 13 and discharging into the line 15 leading to the hot well. A certain constant portion of the condensate is thus free to take the shunt passage directly through the open pipe 16. A valve 17 is provided in the line 13 above its juncture with line 16 and may be utilized when nec- 135 essary for the purpose of regulating the flow of that portion of the condensate which is not accommodated by the pipe 16. By this construction the regulation affects only a fraction of the total volume of flow and may thus be conducted with greater facility than would be the case if the entire fluid stream 140

were controlled by the regulating valve. Closing of the valve 17 to restrict the fluid passage has the effect of increasing the back pressure on the liquid in the pipe 13 and 5 will balance a greater pressure in the return header 7.

I have found that with my invention the height of the loop ordinarily may be from 10 to 15 feet, which length of loop is readily 10 accommodated in the basement beneath the floor upon which the drainage system is mounted. The condensate will normally stand at a level somewhere along the pipe 12, and this level may be varied by opening 15 the valve 17 to a greater or lesser extent. For the purpose of determining approximately where the level of the condensate in the pipe 12 is located a series of test cocks 18 is provided, the uppermost of the cocks 20 which discharges water upon opening indicating that the liquid level is somewhere between that cock and the one next above. It may be noted that the inner ends of the test cocks are curved downwardly to prevent 25 a false indication which might otherwise be obtained due to the condensate flowing down the walls of the pipe 12 being discharged through the test cocks when open.

In the operation of my improved system 30 it is merely necessary to turn on the supply of steam to the main header 4, and the operation of the apparatus continues automatically. I have found that the copper discs containing the orifices may be continuously used without the necessity of varying 35 the size of the orifice, and the proper size of orifice may be initially determined by experiment. After such initial determination it will not subsequently be 40 necessary to change the size of orifice employed although such a change may readily be made merely by substituting a disc having a different sized hole. I have found that the copper discs containing the orifice are more 45 satisfactory than gate valves with a notch for the purpose of forming the constricted portion of the passage, inasmuch as valves are apt to be tampered with and the adjustment of the system thus disturbed. Furthermore, 50 the provision of the orifice discs affords a less expensive and a more rigid and less complicated structure.

For convenience in determining the pressure in the various parts of the system, I 55 provide a gauge 19 preferably capable of registering pressures either above or below atmospheric, and arrange connections to the gauge in such manner that the pressure at any part of the system may be determined. 60 For instance, when the valve 20 in the gauge piping is open and the valves 21 and 22 are closed the gauge will register the pressure in the main steam header. With valve 21 open and the other valves closed the pressure indicated by the gauge is that in the return 65

header 7, while with valves 21 and 20 both closed and valve 22 open the pressure in the line 15 leading to the hot well is determined. In this manner it is possible to determine in a few seconds whether there is sufficient 70 pressure difference between the drying cylinders and the discharge main and whether there is the proper pressure difference between the discharge main and the line 15 to secure a free flow to the hot well. 75

In Fig. 3 I have illustrated a modification in which the vertical pipe loop is dispensed with. In this modification the condensate from the return header 7 flows down into the short vertical pipe or chamber 23 80 and is conveyed thence into the discharge line 15 leading to the hot well partly by means of an open pipe 24 and partly by means of a trap 25. The larger proportion 85 of the condensate passes through pipe 24 while the trap serves to regulate the balance. It is to be noted that this arrangement is more satisfactory than would be the case where the open line 24 is dispensed with and the trap employed alone, for the reason that 90 in the arrangement shown the size of the trap may be materially smaller and the expense of the system correspondingly reduced. It may be of advantage to substitute the trap 25 and its associated pipe 24 in 95 place of the vertical loop when the space beneath the apparatus is particularly limited, as only a small space is required to accommodate the trap.

In Fig. 4 I have illustrated a further manner in which the steam recovered from the return header 7 may be utilized. A heating coil is connected at 27 onto the line 14 which conveys the steam recovered from the return header 7 into the cylinder 1. This coil is 100 for the purpose of heating the air surrounding the drying cylinders and may be useful in certain installations. It is obvious, however, that the connection at 27 may be employed to convey steam to any desired 105 point for utilization in whatever manner may be desirable, or the steam may be partially used to heat one of the drying cylinders and partly for any other appropriate 110 purpose. 115

I have described certain preferred embodiments of my invention, but it is possible that certain variations and changes may be made without exceeding the scope of the invention as defined in the claims. For instance, the cylinder 1 in which is utilized the steam recovered from the main return header need not be located in the position shown but may be any one of the heating 120 elements of the systems. It is further to be understood that while I have described my invention as employed in connection with a system of the type ordinarily employed in paper mills, it is equally applicable to any 125 installation in which revolving drying cyl- 130

inders are employed, such as those used in textile mills for drying cloth, and the like.

I claim:

1. A system of the class described, comprising a plurality of drying cylinders, means for supplying heating steam to said cylinders, means for removing the contents of said cylinders comprising a drainage main and individual drainage connections between the respective cylinders and said main, and means for maintaining a continuous pressure difference between the cylinders and said drainage main comprising a restricted portion of constant area interposed in each of said individual drainage connections. 70
2. A system of the class described comprising a drying cylinder, means for supplying heating steam to said cylinder, means for effecting a discharge from said cylinder comprising a drainage line and connection from the cylinder to said line, and an obstruction in said connection containing an orifice of fixed dimension whereby the flow through said connection is restricted and the pressure in said cylinder raised above that in said drainage line. 80
3. A system of the class described comprising a plurality of drying cylinders, means for supplying heating steam to said cylinders, means for effecting a discharge from said cylinders comprising a drainage main and individual drainage connections between the respective cylinders and said main, means for maintaining a continuous pressure difference between the cylinders and said drainage main comprising a metallic disc containing an orifice of fixed dimension whereby the flow through said drainage connections is restricted. 95
4. A system of the class described comprising a plurality of drying cylinders, means for supplying heating steam to said cylinders, means for effecting a discharge from said cylinders comprising a drainage main and individual drainage connections between the respective cylinders and said main, means for separating the condensate from the uncondensed vapor in said main comprising a passage for deflecting the condensate out of its previous direction of flow and a separate passage for receiving the vapor, and means for conveying said uncondensed vapor to a point of utilization. 100
5. A system of the class described, comprising a plurality of drying cylinders, means for supplying heating steam to said cylinders, means for removing the contents of said cylinders comprising a drainage main and individual drainage connections between the respective cylinders and said main, means for maintaining a continuous pressure difference between the cylinders and said drainage main, means for separating the condensate from the uncondensed vapor in said main comprising a downwardly extending passage for receiving the condensate, whereby the condensate is deflected by the action of gravity from its previous direction of flow and a separate passage for receiving the uncondensed vapor without altering its direction of flow. 115
6. A system of the class described comprising a plurality of drying cylinders, means for supplying heating steam to a number of said cylinders, means for removing the contents of said cylinders comprising a drainage main and individual drainage connections between the respective cylinders and said main, means for separating the condensate from the uncondensed vapor in said main comprising a passage for deflecting the condensate out of its previous direction of flow, and means for supplying said uncondensed vapor as heating medium to the remaining cylinders. 120
7. A system of the class described comprising a plurality of drying cylinders, means for supplying heating steam to a number of said cylinders, means for removing the contents of said cylinders comprising a drainage main and individual drainage connections between the respective cylinders and said main, means for maintaining a continuous pressure difference between the cylinders and said main comprising a restricted portion of constant area interposed in each of said individual drainage connections, a passage at substantially the outlet end of said drainage main for deflecting the condensate away from the uncondensed vapor, a passage for receiving the uncondensed vapor and conveying it into the remaining drying cylinders as heating medium therefor, and means for effecting a continuous discharge therefrom. 130
8. A system of the class described comprising a plurality of drying cylinders, means for supplying heating steam to said cylinders, means for effecting a discharge from said cylinders comprising a drainage main and individual drainage connections between the respective cylinders and said main, a loop passage for receiving and discharging the condensate from said drainage main, one branch of said fluid conveying loop having a portion of restricted cross section for impeding the flow of fluid therethrough. 125
9. A system of the class described comprising a plurality of drying cylinders, means for supplying heating steam to said cylinders, means for effecting a discharge from said cylinders comprising a drainage main and individual drainage connections between the respective cylinders and said main, a vertical fluid conveying loop for re-

ceiving the condensate from said drainage main, the latter branch of said loop being of restricted cross section for retarding the flow of fluid therethrough, whereby a loop 5 of maximum dimension comparable with ceiling height may be employed to balance the pressure in said drainage main.

10. A system of the class described comprising a plurality of drying cylinders, means 10 for supplying heating steam to said cylinders, means for effecting a discharge from said cylinders comprising a drainage main and individual drainage connections between the respective cylinders and said main, a loop 15 passage for receiving and discharging the condensate from said drainage main, the initial branch of said loop being of substantially uniform cross section and the latter branch of said loop having a portion 20 of restricted cross section less than that of the unrestricted portion of said latter branch, whereby a portion of the condensate is discharged through said shunt passage and the remainder through said restricted portion, and means for varying the fluid conveying capacity of said restricted portion.

11. A system of the class described comprising a plurality of drying cylinders, 30 means for supplying heating steam to said cylinders, means for effecting a discharge from said cylinders comprising a drainage main and individual drainage connections between the respective cylinders and said main, a loop passage for receiving and discharging condensate from said drainage main, the latter branch of said loop having a portion of restricted cross section for impeding the flow of fluid therethrough, and 35 a plurality of test cocks provided on the initial branch of said loop, whereby the approximate level of the condensate in said initial branch may be determined.

12. A system of the class described, comprising a plurality of drying cylinders, means 45

for supplying heating steam to said cylinders, means for effecting a continuous discharge from said cylinders comprising a drainage main and individual drainage connections between said respective cylinders and said main, means for maintaining a continuous pressure difference between cylinders and said drainage main, comprising a restricted portion of constant area interposed in each of said individual drainage connections, a 50 loop passage for receiving and discharging the condensate from said drainage main, the initial branch of said loop being of substantially uniform cross section and the latter branch of said loop having a portion of 55 restricted cross section, a shunt passage around said restricted portion of cross section less than that of the unrestricted portion of said latter branch, whereby a portion of the condensate is discharged through 60 said shunt passage and the remainder through the said restricted portion, and means for varying the fluid conveying capacity of said restricted portion.

13. A system of the class described, comprising a plurality of drying cylinders, means for supplying heating steam to said cylinders, means for removing the contents of said cylinders comprising a drainage main and individual drainage connections 70 between the respective cylinders and said main, means for maintaining a continuous pressure difference between the cylinders and said drainage main comprising a restricted portion of constant area interposed 75 in each of said individual drainage connections, a pressure gauge, and connections whereby said pressure gauge may be caused to register the pressure within the drying cylinders, in the drainage main, and in the 80 discharge line, respectively.

In testimony whereof I affix my signature.

GEORGE H. BARRUS.
